HARMONIC INERTIA SNUBBER

Walter B. Whippo, Cayuta, N.Y., assignor to Sperry Rand Corporation, New York, N.Y., a corporation of Delaware

Filed Nov. 30, 1960, Ser. No. 72,631

13 Claims. (Cl. 267—1)

This invention relates to motion checking devices and in particular to means for providing harmonic deceleration for a part moving to a stop, so that the shock and noise normally accompanying stopping of a moving part will be greatly reduced and to a degree not achieved by present stopping devices such as pins, springs, bumpers, dashpots or the like.

A particular object of the invention is to provide a harmonic inertia snubber, the success of which depends on the embodiment of fundamental laws, namely (1) the energy of a system equals the mass times the velocity squared/2; (2) the presence of gravity and inertia in any mass; and (3) the trigonometric functions of a circle; resulting in a device that is simple in structure, and reliable and predictable in operation.

A further object of the invention is to provide a ring and pin combination in which the effectiveness of the device can be controlled by the density of the ring material; the width, thickness and diameter of the ring, and the ratio of the diameter of the ring to the diameter of the pin.

Other objects and structural details of the invention will be apparent from the following description when read in connection with the accompanying drawing, wherein:

FIGURE 1 is a side view of one end of a member to be stopped showing the latter in contact with a ring freely suspended from a pin;

FIGURE 2 is a view similar to FIGURE 1 showing the movement of the ring which shifts the center of gravity thereof from beneath the pin;

FIGURE 3 is a view similar to FIGURE 2 showing the shift of gravity to maximum extent and the limit movement of the part to be brought to a stop;

FIGURE 4 is a view showing the parts in vertical position and counterbalancing means applied to the ring which is arranged to swing vertically to arrest a vertically moving part to be stopped; and

FIGURE 5 is a view similar to FIGURE 4 showing a modified form of ring counterbalancing means that operates to yieldably maintain the ring in a horizontal position.

One example to which my invention may be put, to illustrate the practical use thereof, would be in a business machine in which it is highly desirable to stop a platen carriage movement at the end of its return travel with a minimum of noise and rebound. To this end, 10 indicates the moving part of any member that is to be brought to a stop while moving in a horizontal path and having an end portion 11 that is at least as wide as half the diameter of a stop ring 12 which is suspended freely from a pin 13 that coats with the ring 12 in arresting the movement of the part 10.

The ring 12 can be made from any material and will conform to the laws above mentioned, but I prefer the use of a ring made of nylon which is hung loosely on the pin 13 and at rest assumes a position in a vertical plane.

65

2

The part 10 whose motion is to be stopped moves toward the pin and at its leading vertical end edge 11 contacts the outer surface of the ring first. This contact point is 90 degrees away from the point where the ring 12 contacts the pin from which it hangs. The center of gravity of the ring is normally directly below the pin, but with continued motion of the part 10, to be stopped, towards the pin, the ring 12 is now moved in the same direction as the moving part. As the part 10 moves closer to the pin 13 the center of gravity of the ring designated as at 14 swings in an arc about the pin until it has moved through 90 degrees of revolution, and is at the same level as the pin 13, and the moving part 10 is stopped.

By moving the center of gravity of the ring from beneath the pin, work energy will be extracted from the moving part, and the rate at which this energy is extracted increases as the sine function of the movement of the center of gravity 14 of the ring about the pin. The effect of this transfer of energy is to harmonically reduce the energy of the moving part 10 to zero.

The result of this harmonic reduction of the energy of the moving part is that it approaches its final stopping point with continually decreasing energy and arrives at a dead stop with theoretically no tendency to bounce, vibrate or produce noise, since theoretically all of its energy has been extracted by the motion imparted to the ring. In practice due to efficiency losses, the device will not reach perfection, but the results are dramatically superior to existing snubbers, bumpers and stops, since none of these achieve the cycloidal reduction of momentum necessary to quietness and smooth operation. An additional feature is that a point on the ring precesses around the ring with each operation of the snubber, presenting a new surface after each cycle. This will tremendously increase the durability of the snubber and the reliability of its dimensions over existing snubbers. This device may work in planes other than the vertical, by applying a spring or a counter balance to the device as a substitute for gravity. A spring would produce a variation of the harmonic reduction in energy since it would not apply a constant force throughout its travel, and as illustrated in FIGURE 4, one form of spring 16 is used which may be secured to the ring 15 in horizontal alignment with the pin 17 as at 18 and be held in an adjusting device 19 for varying the tension of the spring. The moving part 17A, provided with a flat top edge 18A, which is substantially as wide as half the diameter of the ring, is in alignment with the pin 17 and engages the outside surface of the ring 15 initially, at a point vertically aligned with the center of gravity designated here as at 20.

In the form illustrated in FIGURE 5 the pin 21 has secured to an inner flattened side thereof the flat portion 22 of a leaf spring having legs 23 which terminate in rounded ends 24 for engagement with the inner periphery of the ring 25. The spring provides the flexible legs 23 which yieldably hold the ring 25 against vertical movement but allow the ring to be pushed by the moving part 26 to alter the position of its center of gravity 27 in accordance with the outline showing in FIGURE 5. Each leg 23 is independently flexible and the lower leg will yield as the ring moves away from the upper leg. The spring acts as a self restoring agent for the ring after the moving part 26 has been retracted.

60 In the form of the invention shown in FIGURE 4, the

adjustment of the spring 16 to increase the tension thereof will provide a greater resistance to the movement of the ring 15 by the part 17A by providing an adjustable gravity simulator. This may also be accomplished by changing the weight of the ring, increasing its diameter or varying the thickness of the stock from which the ring is made.

While there is above described a particular embodiment of the invention, it is possible to produce other embodiments without departing from the inventive concept above disclosed and it is therefore desired that only such limitations shall be imposed on the appended claims as are stated therein, or required by the prior art.

What I claim as new and desire to secure by Letters Patent is:

1. A device for arresting the motion of a moving member, comprising annular means, and a member stationary with respect to said moving member contacting said annular means along a portion of its inner annular surface to support said annular means for swinging movement under influence of said moving member to harmonically decelerate the movement of said moving member.

2. A device for arresting the motion of a moving part, comprising annular means, and a support member stationary with respect to said moving member engaging said annular means along a portion of the inner annular surface thereof to support said annular means for swinging movement to provide harmonic deceleration of said moving part, said annular means at the end of its swinging movement coacting with said support member for providing a stop for said moving part.

3. In a device for arresting the movement of a part having an edge portion, fixed pin means in the path of movement of said edge portion, and ring means supported at one portion thereof by said pin means and arranged to be swung by said edge portion as the latter moves toward said pin means, the center of gravity of the ring means during swinging movement being displaced from a first position through an arc of substantially ninety degrees to provide harmonic deceleration of said moving part until said ring means and pin means arrest the movement of said part.

4. In a device for arresting the movement of a part having a straight edge portion, fixed pin means in the path of movement of said edge portion, ring means supported at one portion thereof by said pin means and arranged to be swung by said edge portion as the latter moves toward said pin means, the center of gravity of the ring means during swinging movement thereof being displaced from an initial position through an arc of substantially ninety degrees to provide harmonic deceleration of said moving part, and tension means associated with said ring means for yieldably resisting movement of said ring means.

5. In a device for arresting the movement of a part having a straight edge portion, fixed pin means in the path of movement of said edge portion, ring means supported at one portion thereof by said pin means and arranged to be swung by said edge portion as the latter moves toward said pin means, the center of gravity of the ring means during swinging movement thereof being displaced from an initial position through an arc of substantially ninety degrees to provide harmonic deceleration of said moving part, tension means associated with said ring means for yieldably resisting movement of said ring means, and means for adjusting said tension means to increase the resistance to movement of said ring means.

6. In a device for arresting the movement of a part having a vertical edge portion, fixed pin means in the path of said edge portion, and ring means having its center of gravity below said pin means and being suspended from said pin means in the path of said edge portion, said ring means being engaged and swung by said edge portion as said part moves closer to said pin means the center of gravity of said ring means swinging in an

arc of substantially ninety degrees about the pin means and to horizontal alignment with said pin means to provide harmonic deceleration of said moving part until the ring and pin means coact to stop said moving part.

5 7. In a device for arresting the movement of a part having a flat edge, fixed pin means in the path of said edge, and ring means having an inner ring surface and disposed with a portion of said inner ring surface in contact with said pin means to be supported by said pin means in the path of said edge for engagement thereby, said ring means having substantially a precessional movement along said edge and providing harmonic deceleration of said moving part as said edge approaches said pin means and until said edge engages that portion of said ring means between said pin means and the said edge to provide a stop.

10 8. In a device for arresting the movement of a part having a flat edge, fixed pin means in the path of said edge, ring means having an inner ring surface and disposed with a portion of said inner ring surface in engagement with said pin means to be supported by said pin means substantially in the path of said edge for engagement thereby, said ring means having substantially a precessional movement along said edge and providing harmonic deceleration of said moving part as said edge approaches said pin means and until said edge engages that portion of said ring means between said pin means and said edge to provide a stop, and yieldable means associated with said ring means for yieldably resisting movement of said ring means.

15 9. In a device for arresting the movement of a part having a flat edge, fixed pin means in the path of said edge, ring means having an inner ring surface and disposed with a portion of said inner ring surface in engagement with said pin means supported on said pin means in the path of said edge for engagement thereby, said ring means having substantially a precessional movement along said edge and providing harmonic deceleration of said moving part as said edge approaches said pin means and until said edge engages that portion of said ring means between said pin means and said edge to provide a stop, and yieldable means associated with said ring means for yieldably resisting movement of said ring means, and means for adjusting said yieldable means to increase the resistance to movement of said ring means.

20 10. In a device as set forth in claim 8 in which said yieldable means includes a spring with one end thereof fixedly positioned and the other end thereof secured to said ring means at a point diametrically opposite said pin means to vary the harmonic decelerating action of said ring means in swinging movement.

25 11. A motion arresting mechanism of the class described, comprising a moving member movable in a predetermined path, a support member stationary with respect to said moving member, and a movable mass having formed therein an aperture defined by a wall and adapted to be mounted on said support member with a portion of said wall in contact with a portion of said support member and in the path of movement of said moving member for engagement by the latter to harmonically decelerate and arrest movement of said moving member, said mass being mounted to provide a center of gravity traversing an arcuate path in arresting motion of said moving member.

30 12. The motion arresting mechanism of claim 11 which includes yieldable means coacting with said movable mass and adapted to oppose movement of said movable mass by said moving member.

35 13. In a device for arresting the movement of a part having a flat edge, fixed pin means in the path of said edge, ring means supported on said pin means and substantially in the path of said edge for engagement thereby, said ring means having substantially a precessional movement along said edge and providing harmonic deceleration of said moving part as said edge approaches

said pin means and until said edge engages that portion of said ring means between said pin means and said edge to provide a stop, and yieldable means associated with said ring means for yieldably resisting movement of said ring means, said yieldable means including a leaf spring with the inner surface of said ring means for yieldably providing diverging leg portions for yieldable engagement with the inner surface of said ring means, and

means for securing said spring to one side of said pin means.
